(57) **CLAIM**

I claim the ornamental design for a bottom-dumping split refuse container with sloped floor, as shown and described.

DESCRIPTION

FIG. 1 is a perspective view of a bottom-dumping split refuse container with sloped floor showing my new design;

FIG. 2 is a top plan view thereof;

FIG. 3 is a side elevational view thereof, the elevational view of the opposing side being identical thereto;

FIG. 4 is a bottom plan view thereof; and

FIG. 5 is an end elevational view, the elevational view of the opposing end being identical thereto; and,

FIG. 6 is a perspective view showing the bottom-dumping split refuse container with sloped floor in use; the broken lines depict environmental structure for illustrative purposes only and form no part of the claimed design.
